FIG. - 2

Inventor

William C. McMurray

Albert E. Synchik
Attorney

UNITED STATES PATENT OFFICE.

WILLIAM C. McMURRAY, OF AVALON, PENNSYLVANIA.

KNOCKDOWN FUSEE AND CARRYING CASE.

Application filed October 6, 1927. Serial No. 234,365.

This invention relates to new and useful improvements in fusees or signalling torches.

One object of my invention is to provide a fusee formed of separable sections, so that the fusee, when not assembled for use, can be readily carried in the pocket of a coat or other garment of a trainman, aviator, boatman, watchman or other operative so as to be available for immediate use.

Another object of my invention is to provide in combination with a knock-down fusee, a safety carrying case in which the sections of the fusee may be packed to protect them from any injury or the deteriorating effect of air and moisture and which will also serve as a handle or holder for the fusee when signalling.

With these objects in view and with the intention of securing other advantages which will hereinafter appear, my invention consists of the features of construction and combination of parts described in the specification, particularly pointed out in the claims and illustrated in the accompanying drawings.

Referring to the accompanying drawings, Fig. 1 is a perspective view of my safety carrying case with the fusee sections packed therein; Fig. 2 is a top view of the same with the top or lid removed; Fig. 3 is a section on line 3—3, Fig. 1; Fig. 4 is a section on line 4—4, Fig. 3; Fig. 5 is a view showing the fusee assembled and mounted on the case, so that the case may be used as a holder for the fusee when it is lit.

Again referring to the drawings, 5 represents the separable combustible sections of my fusee, which are formed of the usual materials. Each section is made complete in itself and the upper end thereof is provided with the usual fulminate or ignition material 6. On the lower end of each of the sections 5 is arranged a sleeve 8 which extends below the end thereof. The projecting portion of the sleeve 8 is designed to slip over and snugly engage the upper portion of another section of the fusee forming a separable but firm and positive connection between the sections.

The base of the fusee is generally made of a piece of wood 9 and is provided with a spike 10, in the customary manner. The upper end of the base 9 is adapted to be firmly engaged by the projecting end of the sleeve 8 on the lowermost section 5.

The fusee is shown completely assembled in Fig. 5 and when thus assembled, instead of mounting it on the case, it may be dropped or thrown from a train and will remain intact after striking the ground, the same as a one piece fusee.

My improved safety case is shown at 12 and may be made of any suitable material. The dimensions of the case 12 are such that the separated sections of the fusee may be snugly packed therein and easily removed therefrom.

In the sides of the case 12 and near the top thereof and in line with each other are formed two openings 14. These openings 14 form sockets for the reception of the spike 10 in the base 9. After the fusee is assembled the spike 10 may be inserted through the openings 14 in the case 12 and the case can then be used as a handle or holder for the fusee when signalling.

A tube 15 extends transversely of the case 12 and the ends of said tube are mounted in the openings 14. The tube 15 prevents moisture or any foreign material from entering the case 12 through the openings 14 and also serves as a guide to facilitate the passage of the spike 10 through both openings 14.

The case 12 is provided with a closely fitting cover or lid 16 which may be hinged thereto in the usual manner or may be made entirely removable. As shown the lid is of the slip over type and in order that it may be held securely in the case the cover or lid is provided with small lugs or bosses 18, which engage with the openings 14 and also with an eyelet 19 which engages a small boss 20 on the case 12.

On the inside of the lid 16 is placed a quantity of the ignition material necessary for striking fire with the fulminate on the combustible sections 5 of the fusee.

The advantages of my knock-down fusee and carrying case will be readily appreciated. An occasion calling for the use of a signal torch or fusee is generally caused by some sudden emergency, and a slight delay or loss of time often involves disastrous results. Owing to the relative cumbersome size of the present one piece fusee it is customary to keep the fusee in some definite place, as on a shelf or rack. When the need for a fusee arises much valuable time is lost in locating and getting it. My fusee in its carrying case will fit into any pocket, so that any train-

man, aviator or other operative, who may have call to use a fusee, can carry a fusee on his person without any inconvenience and have it ready for immediate use.

- 5 The making of the fusee in separable sections affords other advantages. For instance, the sections may be made so that some sections will burn longer than other sections and one section can be ignited at a time according 10 to the length of time it is desired to display the signal. Also if an aviator wishes to give a signal he can select the section or sections of the fusee which will burn out before reaching the ground and thereby avoid fire hazards. 15 Again the sections may be made of different materials so that they will show various colors when being burned and a fusee can then be assembled so that it will show a succession of colors according to some predetermined code. 20

What I claim is:—

1. A fusee formed of independent sections of combustible material, means for connecting the sections together so as to form a continuous fusee and a carrying case for holding 25 the sections when separated.

2. A fusee comprising a plurality of independent sections of combustible material and means for connecting said sections together comprising a sleeve adapted to engage the 30 lower end of one section and the upper end of another section.

3. The combination with a knock-down fusee of a carrying case therefor, adapted to receive the separated sections of the fusee, 35 said case being provided with a socket forming openings to receive the spike of the fusee when the fusee is assembled for use.

In testimony whereof I affix my signature.

WILLIAM C. McMURRAY.
